UNITED STATES PATENT OFFICE

135,661

DESIGN FOR A SPRING SHACKLE BOLT

Erich O. Krauter, United States Army

Application August 19, 1942, Serial No. 107,961

Term of patent 3½ years

To all whom it may concern:

Be it known that I, Erich O. Krauter, United States Army, a citizen of the United States, have invented a new, original, and ornamental Design for a Spring Shackle Bolt, of which the following is a specification, reference being had to the accompanying drawing, forming part thereof.

Fig. 1 is a side elevational view of a spring shackle bolt, showing my new design, and

Fig. 2 is an end elevational view thereof.

The dominant feature of the design resides in

a central general cylindrical portion having its surface composed of a single, continuous, narrow, flat, sharp-edged band extending in a plurality of helical convolutions, the edges of the adjacent convolutions of the band being separated by a relatively deep groove narrower than the width of the band.

I claim:

The ornamental design for a spring shackle bolt, as shown and described.

ERICH O. KRAUTER.
